US00D831585S

(12) **United States Design Patent** (10) **Patent No.:** **US D831,585 S**
(45) **Date of Patent:** **** Oct. 23, 2018**

(54) **CONTROLLER FOR HOME AUTOMATION DEVICES**

(71) Applicant: **LG ELECTRONICS INC.**, Seoul (KR)

(72) Inventors: **Hophil Lee**, Seoul (KR); **Kyounjoung Kim**, Seoul (KR); **Bonghui Kang**, Seoul (KR)

(73) Assignee: **LG ELECTRONICS INC.**, Seoul (KR)

(**) Term: **15 Years**

(21) Appl. No.: **35/502,282**

(22) Filed: **Jul. 7, 2016**

(80) **Hague Agreement Data**

Int. Filing Date: **Jul. 7, 2016**

Int. Reg. No.: **DM/092852**

Int. Reg. Date: **Jul. 7, 2016**

Int. Reg. Pub. Date: **Jan. 13, 2017**

(30) **Foreign Application Priority Data**

Jan. 7, 2016 (KR) 30-2016-0000705

(51) **LOC (11) Cl.** **13-03**

(52) **U.S. Cl.**

USPC **D13/162**

CLAIM

The ornamental design for a controller for home automation devices, as shown and described.

DESCRIPTION

1. Controller for home automation devices

1.1 is a perspective view;

1.2 is a front view;

1.3 is a rear view;

1.4 is a side view;

1.5 is a side view;

1.6 is a top view;

1.7 is a bottom view;

1.8 is a perspective view shown in an environment; and

1.9 is another perspective view shown in an environment.

The broken line showing of the plurality of circular features in figure 1.3 is for the purpose of illustrating portions of the controller for home automation devices and forms no part of the claimed design; the broken line showing in figures 1.8 and 1.9 is for the purpose of illustrating environmental structure and forms no part of the claimed design.

1 Claim, 9 Drawing Sheets
